UNITED STATES PATENT OFFICE

WILLIAM E. CROWLEY, OF LAMBERTVILLE, NEW JERSEY, ASSIGNOR TO LAMBERTVILLE RUBBER COMPANY, INC., OF LAMBERTVILLE, NEW JERSEY, A CORPORATION OF NEW JERSEY

DESIGN FOR A SHOE SOLE

Application filed September 19, 1929. Serial No. 32,792. Term of patent 14 years.

To all whom it may concern:

Be it known, that I, WILLIAM E. CROWLEY, a citizen of the United States, residing at Lambertville, in the county of Hunterdon and State of New Jersey, United States of America, have invented a new, original, and ornamental Design for Shoe Soles, of which the following is a specification, reference being had to the accompanying drawing, forming part thereof.

Figure 1 is a plan view of a shoe sole showing my new design.

Fig. 2 is a transverse section on line 2—2 of Fig. 1, and Fig. 3 is a like section on line 3—3 of Fig. 1.

I claim:

The ornamental design for a shoe sole as shown.

WM. E. CROWLEY.
